FIG. 1 is an environmental perspective view of a oil lamp
showing my new design;FIG. 2 is a front elevational view with the rear view being
a mirror image thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a cross-sectional view of FIG. 2 thereof.

The broken line showing of the oil, the flame, and the base
in FIGS. 1 and 2 is for illustrative purposes only and forms
no part of the claimed design.
